UNITED STATES PATENT OFFICE.

HENRY C. STRACK, OF OWEGO, NEW YORK.

SHARPENING DEVICE.

1,229,668.

Specification of Letters Patent. Patented June 12, 1917.

Application filed May 11, 1916. Serial No. 96,757.

To all whom it may concern:

Be it known that I, HENRY C. STRACK, a citizen of the United States, and a resident of Owego, Tioga county, State of New York, have invented a certain new and useful Improvement in Sharpening Devices, of which the following is a specification.

My invention relates to sharpening devices, and more particularly to an apparatus for honing and stropping safety razor blades, and has for its object to produce a device which may be used either for honing or stropping and which may be readily changed from one to the other.

15 A further object is to produce a device in which the sides of the edge of the blade will be automatically presented to stropping or honing surface at the proper angle, and held in such relationship by a uniform pressure.

20 A further object is to provide means for securely holding the blade in proper position relatively to the abrading or setting surface.

25 A further object is to provide means whereby the abrading and edge-setting surfaces may be readily renewed.

A still further object is to provide for the ready insertion or removal of the blade.

30 These and further objects will more fully appear in the following specification and accompanying drawings, considered together or separately.

I have illustrated my invention in the accompanying drawings in which similar reference characters designate corresponding parts in all the figures, and in which,

Figure 1 is a top plan view;

Fig. 2 is a longitudinal section taken on the line 2—2 of Fig. 1;

Fig. 3 is a section on the line 3—3 of Fig. 2;

Fig. 4 is a detail section taken on the line 4—4 of Fig. 2;

45 Fig. 5 is an enlarged detail sectional view of the blade-retaining means;

Fig. 6 is a fragmentary front elevation of a portion of the blade-retaining means;

Figs. 7, 8, 9, and 10 are diagrammatic views showing the positions of the parts during the forward movement;

Fig. 11 is a detail sectional view showing a heavy backed blade in position;

55 Fig. 12 is an enlarged sectional view showing the manner of attachment of the setting and abrading surfaces;

Fig. 13 is a top plan view of a modification;

Fig. 14 is a section on the line 14—14 of Fig. 13;

Fig. 15 is a detail sectional view showing the blade carrier opened; and

Fig. 16 is a rear elevation of the form of device shown in Figs. 13, 14, and 15.

In the embodiment of the invention illustrated in Figs. 1 to 12 I have shown a device for honing and stropping single edge safety razor blades, and in Figs. 13 to 16 a device for honing and stropping double edge blades of the Gillette and Durham duplex type.

In the drawings 1 designates a body of box-like form having its front end 2 concaved to form a seat for the thumb and its rear end 3 concaved for engagement by the fingers of the operator. The body is of a size to conveniently fit in the palm of the hand with the thumb resting in the concavity of the front wall and the fingers engaging the concave rear wall. The sides 4 and 5 of the body 1 are provided with standards 6, extending above the sides of the box.

Journaled in the side walls 4 and 5, and in line with the center of the standards, is a shaft 7 to which is rigidly secured a frame 85 comprising side arms 8, 8, and a table 9. The table extends across the arms 8 and is provided with a slightly convex top and with wings 10, 10 extending upward at right angles thereto.

An operating shaft 11 is journaled in the sides 4 and 5 near the front 2 of the body, and carries at one end an operating crank 12, and at the other end a crank 13. A pawl and ratchet 14 coöperate with the shaft 11 to 95 prevent backward movement of the same. The pawl and ratchet may, however, be dispensed with if desired.

A lever 15 is pivoted to the crank 13, and a lever 16 carried by the shaft 7 is pivoted at its extremity to the end of the lever 15, which latter is provided with a double cam-faced extension 17 for a purpose to be hereinafter described.

A plate 18, having an enlargement 19 at 105 each end, is provided with trunnions 20, by means of which it is pivoted in the upper ends of the standards 6. The trunnion at one end is provided with a depending tongue 21, which is arranged in the path of the extension 17 when the operating crank is rotated. The crank 13 and the levers 15 and

16 are so proportioned and arranged that a complete rotation of the shaft 11 will rock the shaft 7 and the table 9 through an arc of approximately 90 degrees.

5 A leaf 22 is pivoted to the enlargements 19 of the plate 18, and is provided at each end with an upwardly extending finger 23, each of which is located opposite a similar finger 24 on an enlargement of the plate 18.

10 A spring 25 is positioned between each pair of fingers and tends to normally hold the leaf 22 in contact with the plate 18. One of the fingers 23 is provided with an extension which carries a finger piece 26. One of the

15 enlargements 19 is provided with an arm 27, and a spring 28, which is anchored to the side 4 vertically below the center of the enlargement, is attached to the free end of the arm. This spring will normally hold the

20 plate 18, leaf 22 and arm 27, in their vertical positions and permit them to be swung to either side thereof.

The center of the plate 18 is provided with a bearing 29 carrying a shaft to which is 25 pivoted a wing 30, which has pivoted thereon a spring latch 31. One end of the latch has a tooth for engagement with one of a series of notches 32 in the bearing 29.

30 The honing member 33 and stropping member 34 are secured to the surface of a bed piece 35, which rests upon the table 9 and is embraced by the wings 10. The bed piece is of elliptical cross-section and of a length somewhat greater than the longest 35 safety razor blade. It is preferably made hollow for the sake of lightness, and its surface is foraminous. The ends of the bed piece are recessed, as at 36, and the wings 10 engage these recesses. The wings do not 40 make close contact with the bottoms of the recesses. This will permit the bed piece to have a rocking movement on the convex surface of the table 9.

45 The honing and stropping members are preferably secured to the surface of the bed piece by means of cement 37 which will, when the members are forced into position, be forced through the foraminations in the bed piece and, on hardening, securely retain 50 the members in position.

55 The stropping member is a piece of suitable leather, and the honing member may be a piece of suitable stone or slate cut to proper size, but is preferably of leather, canvas or the like, coated or impregnated with a suitable abrading material, of which crocus Martis is an example.

60 In the embodiment of the invention illustrated in Figs. 13 to 16 I have shown a device particularly adapted for use upon blades of wafer or ribbon type, and having slots or perforations therein. In these figures the device, except for the blade holding mechanism, is identical with that shown in 65 Figs. 1 to 12.

In Figs. 13 to 16 a plate 18^a, similar to the plate 18, is employed, but is disposed nearer the front of the device than is the plate 18. The plate 18^a has enlargements 19^a, trunnions 20^a, an arm 27^a to which is attached a spring 28^a. The plate 18^a is made somewhat thicker than the plate 18, and is provided with a vertical slot 40, extending there-through and having a length sufficient to accommodate the longest safety razor blade. 70 The plate 18^a is provided with a series of perforations 39. A leaf 22^a is pivoted to the enlargements 19^a and disposed at the back of the plate 18^a. The leaf is provided with a series of studs or projections 41. The leaf is, by means of a spring 25^a, normally held in engagement with the back of the plate 18^a with the studs projecting into the 75 perforations. The ends of the studs are bevelled or conical. 80

The operation of the form shown in Figs. 1 to 12 is as follows:

The parts being in the position shown in Fig. 2, the latch 31 is depressed unlocking the wing 30, which is swung back as shown in dotted lines. The device is held in the left-hand with the thumb engaging the wall 2, and the fingers engaging the rear 3. The finger piece 26 may now be engaged by the index finger of the left-hand, and moved 90 backward. This will swing the plate 18 and leaf 22 on the trunnions 19 toward the front until the tongue 21 engages a stop 38 on the standard 6. This will arrest the movement of the plate 18 and the continued 95 depression of the finger piece will swing the leaf relatively to the plate and open the gap between them. A razor blade may now be inserted in the gap with its edge protruding the proper distance below the edges of the 100 plate and leaf. The wing 30 will now be 105 swung into position engaging the back of the blade and locked by the engagement of the latch with a notch in the bearing 29. On the removal of the finger from the piece 110 26 the spring 28 will move the parts to the position shown in Fig. 2. The bed 32 having been placed in position on the table 9 with the surface 24 upward, the device will be in position for honing. 115

The handle 12 being rotated in a clockwise direction will, through the intermediary of the crank 13, and levers 15 and 16, oscillate the table 9 and with it the bed 35. The stropping surface will engage one 120 side of the blade, as in Fig. 7, and the blade will, by the tension of the spring 28, remain in contact with the strop until the parts reach the position shown in Fig. 8, the blade and its carrier being swung by the engagement of the strop with the blade. When the parts reach the position shown in Fig. 8 125 the extension 17 will overtake the tongue 21 and move the blade out of contact with the strop. The continued movement of the 130

strop in the clock-wise direction will move the strop from below the blade carrier, and the extension moving from below the tongue, the spring 28 will return the blade carrier to its initial position. It will be observed that the strop is moving in the direction away from the edge of the blade when the latter is raised, and therefore there is no danger of the edge of the blade being rounded.

10 The continued movement of the crank 12 will, on account of the difference in length of the levers 13 and 16, now swing the strop in a counter-clock-wise direction and it will engage the other side of the blade in the manner above described. When the center of the strop reaches the edge of the blade the back of the extension 17 will engage the back of the tongue 21 and the blade will be raised from contact with the strop as before.

20 The action of the springs 25 on the blade will prevent its being drawn from the carrier by the friction of the strop or hone, and the wing 30 will prevent its being thrown outward by centrifugal force.

25 For use with a double-edge blade the wing 30 may be dispensed with, and the frictional engagement of the plate 18 and leaf 22 be depended on to secure the blade in position.

30 When it is desired to remove the blade from the carrier or to insert one therein the table 9 is moved to the position shown in Fig. 10, the finger piece 26 is depressed, swinging the carrier forward until it is in a horizontal position, and the tongue 21 engages the strop 38. The continued movement of the finger piece will compress the spring 25 and release the leaf 22 from engagement with the blade, which may then be withdrawn from between the leaf and the plate 18 and a new blade substituted. The horizontal position of the carrier will facilitate access to the blade and carrier, and the distance to which the edge of the blade protrudes from the holder may be accurately determined.

40 When it is desired to use the hone the bed piece is reversed and the operation above described is continued.

45 The pawl and ratchet 14 will prevent backward movement of the parts and prevent cutting the strop or injuring the blade by the hone.

50 The stropping and honing surfaces being secured to the bed piece by means of glue or cement may easily be replaced when desired.

55 The convex table 9 will allow sufficient play of the bed piece to permit it to accommodate itself to the edge of the blade should the latter be unevenly placed in the carrier.

60 The operation of the form of device shown in Figs. 13 to 16 is precisely the

same as that above described, except that as 65 a double edge blade is acted on the wing 30 is dispensed with. The blade is inserted in the slot and the spring 25^a will retain the studs 41 in engagement with the perforations or slot in the blade which will therefore be secured against movement in any direction.

70 When it is desired to remove the blade or place a new one in position, the carrier is rotated by the finger piece 26^a until it assumes 75 a horizontal position and the finger 23^a contacts with a stop 42, which will arrest the movement of the leaf 22^a and the continued movement of the plate 18^a will cause the withdrawal of the projections, and the slot 80 40 will be open.

75 In accordance with the provisions of the patent statutes, I have described the principle of my invention, together with the apparatus which I now consider to represent the 85 best embodiment thereof; but I desire to have it understood that the apparatus shown is merely illustrative, and that the invention may be carried out in other ways.

80 Having now described my invention, what 90 I claim as new and desire to secure by Letters Patent, is:—

1. A device of the character described, having a support for a razor blade, an oscillatory frame, a bed piece carried by the 95 frame, there being a stropping surface on one side of the bed piece and a honing surface on the opposite side of the bed piece, means for automatically alining the surface of the bed piece with the edge of the blade, 100 and means for oscillating the frame.

2. A device of the character described, having a support for a razor blade, an oscillatory frame, a bed piece carried by the 105 frame, there being a stropping surface on one side of the bed piece and a honing surface on the opposite side of the bed piece, a convex table on the frame for automatically alining the surface of the bed piece with the 110 edge of the blade, and means for oscillating the frame.

3. A device of the character described, having a body, a support for a razor blade pivoted in the body, a shaft, a frame carried 115 on the shaft, said frame carrying a sharpening surface, an operating spindle, and connections between the spindle and shaft whereby the rotation of the spindle will oscillate the shaft and with it the sharpening surface to oscillate the blade support.

4. A device of the character described, having a body, a support for a razor blade pivoted in the body, a shaft, a frame carried on the shaft, said frame carrying a sharpening surface, an operating spindle, connections between the spindle and shaft whereby rotation of the spindle will oscillate the shaft and with it the sharpening surface to 125

oscillate the blade support, and independent means operable by the rotation of the spindle for rocking the blade support.

5. A device of the character described, having a body, a support for a razor blade pivoted to the body, a spring for securing a blade in position in the support, a frame carried on the shaft, said frame carrying a sharpening surface, an operating spindle, connections between the spindle and shaft whereby rotation of the spindle will oscillate the frame and engage the sharpening surface with a blade carried in the support, the engagement of the sharpening surface with the blade acting to oscillate the blade support, and a spring for holding the blade in engagement with the surface.

6. A device of the character described, having a body, a support for a razor blade pivoted to the body, a frame carried on the shaft, said frame carrying a sharpening surface, an operating spindle, connections between the spindle and shaft whereby rotation of the spindle will oscillate the frame and engage the sharpening surface with a blade carried in the support, the engagement of the sharpening surface with the blade acting to oscillate the blade support, a spring for holding the blade in engagement with the surface, and means for oscillating the support to move the blade away from the sharpening surface.

7. A device of the character described, having a body, a support for a razor blade pivoted in the body, a shaft carried in the body, a frame projecting from the shaft, said frame carrying a sharpening surface at its free end, an operating spindle, connections between the spindle and shaft whereby the rotation of the spindle in one direction will oscillate the sharpening surface, the engagement of the sharpening surface with a blade carried in the support acting to rock the support in the direction of travel of the sharpening surface, a spring for yieldingly engaging the blade with the sharpening surface, and means operable by the rotation of

the spindle for raising the blade from engagement with the sharpening surface before its limit of travel is reached.

8. A device of the character described, having a body, said body having concaved opposite walls, a pivoted support for a razor blade in the body, a shaft journaled in the body, an operating spindle, a crank on the spindle, a lever on the crank, a lever on the shaft, connections between the levers whereby the rotation of the spindle will oscillate the shaft, a frame carried by one end on the shaft and having a sharpening surface carried in the free end of the frame and engaging and oscillating the blade on the oscillating of the shaft, and means engaging the back of the blade for securing the same in the support, and means for releasing the blade from the support.

9. A device of the character described, having a body, a frame pivoted in the body, a table on the frame, and arms on the table, in combination with a bed piece having notches therein and carrying an abrading surface, said bed piece resting on the table and said arms engaging the notches.

10. A device of the character described, having a body, a frame pivoted in the body, a convex table on the frame, and arms on the table, in combination with a bed piece having notches therein and carrying an abrading surface, said bed piece resting on the table and said arms engaging the notches.

11. A device of the character described, having a body, a frame pivoted in the body, a table on the frame, and arms on the table, in combination with a bed piece having notches therein, said bed piece resting on the table and said arms engaging the notches, said bed piece having a stropping surface and a honing surface thereon.

This specification signed and witnessed this fourth day of May, 1916.
